UNITED STATES PATENT OFFICE.

WILLIAM E. GROTE, OF NEW YORK, N. Y.

PHOTOGRAPHIC-PRINTING MACHINE.

1,159,373.

Specification of Letters Patent.

Patented Nov. 9, 1915.

Application filed November 5, 1914. Serial No. 870,423.

To all whom it may concern:

Be it known that I, WILLIAM E. GROTE, a citizen of the United States, residing at New York, in the county of New York and State 5 of New York, have invented certain new and useful Improvements in Photographic-Printing Machines; and I do hereby declare the following to be a full, clear, and exact description of the invention, such as will 10 enable others skilled in the art to which it appertains to make and use the same.

My present invention relates to an improved means for rapidly and accurately handling photographic negatives and sensitive 15 sheets in the operation of printing, and more particularly to apparatus of this character especially adapted to printing successive photographs from different negatives, one at a time, and disposing of the same 20 automatically until ready for the operation of development.

My invention supplies means capable of use in a dark room whereby artificial light may be used without danger of its affecting 25 any sensitive plates, films or paper in the room, not intended to be affected.

While the broad principles of my invention are capable of embodiment in a variety of forms which will readily occur to 30 those skilled in the art, I prefer the form shown in the accompanying drawings wherein—

Figure 1 is a side elevation of the apparatus as arranged for foot power, Fig. 2 is a 35 front elevation of the same, Fig. 3 is a partial median section, Figs. 4, 5, 6, 7 and 8 are partial views of details of the constructions of the movable carrier, and Fig. 9 shows two screens for a special purpose hereinafter 40 described.

The apparatus as a whole comprises a light chamber containing electric lights behind a front glass plate affording an adjusting abutment for the negative and printing paper during printing, in combination 45 with a movable carrier adapted to carry the negative and printing paper into position against said glass.

One improvement preferably associated 50 with the elements above named is an automatic arrangement of circuits whereby the

electric lamps within the light chamber are lighted only when the negative is in printing position.

Another preferred improvement supplies 55 means whereby the negative and undeveloped positive are automatically deposited in a suitable container immediately after printing, so that the apparatus is ready at once for printing another negative. 60

I have shown my device as constructed for printing from films, but, of course, the printer can be adapted to use with glass plates by changes which will be obvious.

The light box 10, which may have any 65 convenient shape and size, is mounted upon a frame 11, which also carries the parts controlling the movable carrier. This carrier preferably takes the form of a table 12, so mounted as to swing around its lower horizontal edge, so that it may be brought flat 70 up against the glass plate 13, which closes the front of the light box (see Fig. 3).

A suitable number of electric lamps 14 are 75 suitably arranged within the box and a small red lamp 15 may be placed upon the same, to facilitate work in the dark room. The circuit which feeds the lamps 14 is interrupted at two opposed springs 16, preferably on one side of the box 10; but, when the table 80 12 is swung up into printing position, the gap at 16 is closed by a lance shaped pin 17, which, by its shape, also tends to hold the table in place by engaging with said springs. It follows that the lamps 14 are automatically lighted, by closing of their circuit, 85 each time that the table 12 assumes the printing position.

When in the inoperative position shown in Figs. 1 and 2, the table 12 rests so that 90 the bowed springs 18 attached to its front or under side are supported upon a swinging frame 19, pivotally suspended upon the bar 20, and controlled by a pedal 21, connected with the frame 19 for this purpose 95 by means of the toggles 22.

In the preferred form shown the support of the lower edges of the negative and sensitive sheet is afforded by a movable ledge, comprising a thin strip 23 adapted to slide 100 in and out within a closely fitting groove near the bottom of the table 12. As shown

in Fig. 7, this ledge is preferably provided with pins 24 at its ends adapted to slide in suitable slots in the table 12, to limit in and out movements of said ledge (see dotted lines in Figs. 4 and 5). When the table 12 is tilted forward, as in Figs. 1 and 5 the forward edge of the ledge 23 abuts against a stop 25, which thrusts it back into position to support the lower edge of the sensitive sheet 26, as in Fig. 5.

The lower edge of the negative 27 rests upon the inner portion of a curved frame 28, adapted to slide within grooves 29, below the table 12, said frame having an inner upturned lip 30 intended to confine the negative 27 during printing, and so proportioned as to cover only the clear undeveloped border around the negative picture. At each side of the frame 28, a spur 31 extends forward through a socket 32 fixed below and in front of the table 12. These spurs are provided with heads between which and the fixed sockets 32 are mounted springs 33, which act to impel the frame 28 forward into the position shown in Fig. 3, whereby the lower edge of the negative 27 is gripped. Immediately behind the supporting edge of the frame 28 is a large opening 34, through which the negative and print are free to fall when the frame 28 is in the position shown in Fig. 4.

In operating the machine, the sensitive sheet is placed upon the ledge 23 and the negative upon the frame 28, in which position the forward ends of the spurs 31 impinge upon the stops 25, thereby holding the lip 30 away from the table 12, as shown in Fig. 5. Upon then pressing the pedal 21, and swinging the table 12 upward, the first effect is to liberate the ledge 23 and the frame 28 from confinement by the stop 25, whereupon the springs 33 cause the frame 28 to slide forward until the lip 30 clips the negative and forces the sliding ledge 23 forward as shown in Fig. 3. When the table 12 assumes the printing position, the negative and sensitive sheet are pressed against the glass 13, and the lamps 14 are automatically lighted as heretofore explained. At the same time, a knob 35, acting as a retaining means, on the end of and behind the frame 28, is embraced by a spring on springs 36 on the box, which latter serves also as an abutment, so that, in the final printing position, all moving parts are held firmly in place, as shown in Fig. 3. After a sufficient exposure, the table 12 is allowed to drop back again. As it first leaves the printing position, the spring or springs 36 act to hold back the sliding frame 28, causing it to assume the position shown in Fig. 4. This permits the negative 27 and undeveloped print 26 to fall through the opening 34. These are caught by an open door

37, whose lower edge is hinged in front of 65 the opening to a box or container 38, into which the negatives and prints drop as soon as released. As the table 12 continues to drop forward, the tension of the springs 33 finally becomes sufficient to withdraw the 70 knob 35 from the spring socket 36.

Where negatives or prints of different sizes are to be accommodated, or where only a part of a full sized negative is to be printed, thin opaque screens may be used 75 having light openings of proper sizes and shapes. Two of these are indicated at 39 in Fig. 9. They may be combined with the apparatus hitherto described by providing a suitable narrow slit behind the glass 13, 80 whereby the screen may be slid down into place within the box 10, as shown at 39 in Fig. 3.

It will be seen that my invention provides a simple and reliable apparatus whereby 85 prints may be rapidly produced, and automatically deposited preparatory to development.

Various changes may be made in the structure and arrangement of my apparatus, 90 without departing from the scope of my invention, and I do not limit myself to the details herein shown and described.

What I claim is—

1. In apparatus for printing photographs, 95 a light box closed on one side by a transparent plate, a movable table for the negative and sensitive sheet, a ledge mounted to slide in a close fitting groove in said table, and a stop arranged to impinge upon said 100 ledge when said table is brought forward.

2. In apparatus for printing photographs, a light box closed on one side by a transparent plate, a movable table for the negative and sensitive sheet, a movable ledge 105 mounted on said table and adapted to receive the edge of a sensitive sheet, a sliding frame supported on said table below said ledge and having an upturned lip, and a spring tending to push said frame forward, substantially as described.

3. In apparatus of the character described, a movable table for the negative and sensitive sheet, a sliding frame mounted on said table and having an upturned lip, a spring 115 tending to push said frame forward, and a stop impinging on said frame to push it backward in one position of said table, substantially as described.

4. In apparatus of the character described 120 a movable table for the negative and sensitive sheet, a sliding frame mounted on said table and having an upturned lip, a spring tending to push said frame forward, a light box toward which said table and frame are 125 adapted to move, and means adapted to oppose a temporary resistance to the springs on said frame so as to draw the frame back-

ward during the beginning of forward movement of said table, substantially as described.

5. In apparatus of the character described, a movable table for the negative and sensitive sheet, a sliding frame mounted on said table, comprising a ledge limited by an upturned lip at the back and by an opening at the front, spurs on said frame, sockets re-

ceiving said spurs, and springs on said spurs, abutting on said sockets, substantially as described.

In testimony whereof, I affix my signature, in presence of two witnesses.

WILLIAM E. GROTE.
